UNITED STATES PATENT OFFICE

146,492

DESIGN FOR A GAME APPARATUS

Wayne L. Thompson, Eightyfour, Pa., assignor to Toyad Corporation, Pittsburgh, Pa., a corporation of Pennsylvania

Application July 30, 1945, Serial No. 121,066

Term of patent 14 years

(Cl. D34—5)

To all whom it may concern:

Be it known that I, Wayne L. Thompson, a citizen of the United States, residing in Eightyfour, in the county of Washington and State of Pennsylvania, have invented a new, original, and ornamental Design for a Game Apparatus, of which the following is a specification, reference being had to the accompanying drawing, forming part thereof.

In the drawing, the figure is a perspective view of a game apparatus embodying my design. The back edge of the game apparatus is plain and unornamented.

I claim:

The ornamental design for a game apparatus, substantially as shown and described.

WAYNE L. THOMPSON.
